UNITED STATES PATENT OFFICE.

FREDERICK W. MOFFAT, OF WESTON, ONTARIO, CANADA.

ELECTRIC HEATING ELEMENT.

Application filed January 28, 1928. Serial No. 250,241.

This invention relates to electric heating elements such as used in the cooking tops of electric stoves and ranges. In such elements it is known to provide a grooved disk in which coiled resistance wiring is positioned. In some cases the disk is formed of insulating material and the grooves face upwardly. In the case of what is known as a "closed" element the disk is formed of metal and the grooves face downwardly, the resistance wiring being retained in position by suitable insulation. In either case it is very desirable that unequal heating of the different parts of the disk be avoided, since in the case of a metal disk this results in warping and warping is disadvantageous as it is important that the heating surface shall be and remain a plane surface and because warping tends to break up any insulation used for the heating elements; and in the case of a disk or porcelain, or similar insulating material, unequal heating results in the cracking of the disk itself. My aim therefore is to produce a heating element less subject to warping and cracking than those at present in use.

I attain my object by forming a circular disk for supporting the resistance wiring with two spiral grooves starting at substantially diametrically opposite points, the said grooves being for the most part concentric with the rim of the disk but each jogged at substantially opposite points a distance equal to the width of a groove, whereby the outer walls of the grooves at the rim of the disk are for the most part of even thickness. As evenness of heating of the disk from center to circumference is the ideal aimed at, I find it advantageous to increase the width of the grooves, and thus the spacing of the convolutions of the resistance wiring, as the center is approached. The heating effect, as compared with evenly spaced convolutions is thus reduced as the center is approached.

The invention is hereinafter more fully described and illustrated in the accompanying drawings in which

Fig. 1 is a plan view of the underside of the metal top of a closed element;

Fig. 2 a cross section of a complete element; and

Fig. 3 a similar view of an element using a porcelain disk.

55 In the drawings like numerals of refer-

ence indicate corresponding parts in the different figures.

From the drawings it will be seen that the top of the element is formed of a disk 1 having ribs 2 and 3 integral therewith, 60 the mean thickness of each rib being approximately the same as the thickness of the disk itself. Usually, for an enclosed element, the disk and ribs will be formed of metal, but the construction and arrangement of the disk with its ribs is applicable also for use with an open heating element, in which case the disk and ribs may be formed of the ordinary so-called porcelain employed for this purpose, or any substitute therefor. 65

The rib 2 is circular in form and is located as close as possible to the circumference of the disk. The ribs 3 alternate and each is formed with a plurality of alternating convolutions. The ribs 3 start and end, it will 70 be noticed, at substantially diametrically opposite points. Ordinarily such ribs are formed as true spirals. In my element, however, the ribs are for the most part concentric with the rib 2, but are jogged at 75 substantially diametrically opposite points a distance equal to the width of a groove formed by the ribs. With this arrangement, the resistance wiring is positioned as close as possible to and almost entirely concentric with the periphery of the disk. A slight gap occurs where a heating element starts adjacent the periphery of the disk, but the passing of the other element just 80 behind this point compensates for the ineffective portion of the element. The whole purpose of the specific construction of the 85 top is to secure an equality of heating effect, and this is materially aided by increasing the spacing of the ribs towards the center of the disk, so as to reduce the heating effect 90 as the center is reached. By the mainly concentric arrangement of the ribs, and consequently the grooves, and the careful spacing of the latter, I attain the desired equalization 95 of the heating effect and prevent the warping which ordinarily tends to crack the top or render the cooking surface uneven.

When the top is made of metal, the resistance wiring requires to be secured in position in the grooves and fully and permanently insulated from the metal. For this purpose I employ a series of insulating blocks 8 mainly open at their sides adjacent the disk. 105 110

The top is supported on a metal pan 4 filled with an insulating cementitious material. Insulating hubs 5 extend through the bottom of the pan close up to the under side of the top and each hub is provided with lugs 6 by means of which it is bolted to the bottom of the pan. The ends of the resistance wiring are brought down through holes in these lugs and are secured to the terminal bolts 7 which pass through holes formed in the hubs, which are counterbored to form shoulders for engagement by the heads of the bolts. The terminals are thus completely insulated and the ends of the resistance wiring brought through for connection well away from the hottest points of the element.

The construction described forms a closed heating element approximating the heating speed of the ordinary open element. At the same time the element is durable, while the resistance wiring and its connections are perfectly insulated and protected.

It will be noted that the outer rib 2 is bevelled so that it will slightly overlap the edge of the pan 5, thus tending to prevent liquids spilt on the top from flowing down over the edge and working in between the top and the support.

When the disk is made of porcelain, it is used with the grooves facing upwardly, as shown in Fig. 3, and the resistance wire is held down by the lips 9.

When the disk is made of metal, the grooves will usually be formed substantially rectangular in cross section.

What I claim as my invention is:

1. A heating element comprising a circular disk having independent ribs integral therewith of even thickness throughout their

length forming two grooves, the said grooves being for the most part concentric with the rim of the disk but each jogged at substantially diametrically opposite points a distance equal to the width of a groove, whereby the resistance wiring of the element is positioned as close as possible to and almost entirely concentric with the periphery of the disk.

2. A heating element comprising a circular disk having integral therewith a circular rib adjacent its rim and two independent parallel ribs having a plurality of convolutions starting at substantially diametrically opposite points and forming grooves, the said ribs being for the most part concentric with the aforesaid circular rib but each jogged at substantially diametrically opposite points a distance equal to the width of a groove, whereby the resistance wiring of the element is positioned as close as possible to and almost entirely concentric with the periphery of the disk.

3. A heating element constructed as set forth in claim 1 in which the grooves adjacent the center of the disk are wider than those adjacent the rim.

4. A heating element constructed as set forth in claim 1 in which the disk and ribs are of approximately the same thickness.

5. A heating element constructed as set forth in claim 1 in which the disk and ribs are of approximately the same thickness, and the grooves formed by the ribs of substantially rectangular cross section.

Signed at Toronto, Canada, this 5th day of January, 1928.

FREDERICK W. MOFFAT.
